VALVE ACTUATING UNIT FOR A PORTABLE FIRE EXTINGUISHER OR SIMILAR ARTICLE

Arduino Riuli, Clifton, and George I. Schrank,
Teaneck, N.J.

Application March 16, 1959, Serial No. 55,017

Term of patent 14 years

(Cl. D16—2)

Fig. 1 is a front elevational view of a valve actuating unit for a portable fire extinguisher or similar article embodying our new design, the rear not shown being substantially plain;

Fig. 2 is a top plan view thereof, with a portion of the discharge nozzle being shown in section and a portion of a housing for a pressure gauge being shown in section to illustrate gauge glass, the bottom not shown being substantially plain; and

Fig. 3 is a right side elevational view on a slightly smaller scale.

We claim:

The ornamental design for a valve actuating unit for a portable fire extinguisher or similar article, substantially as shown and described.
